UNITED STATES PATENT OFFICE.

THOMAS A. KILLMAN, OF NASHVILLE, TENNESSEE, ASSIGNOR OF TWENTY-SIX AND ONE-FOURTH ONE-HUNDREDTHS TO WILLIAM L. DANLEY, OF NASHVILLE, TENNESSEE, ONE-TENTH ONE-HUNDREDTH TO EDWARD H. ROY, OF TULLAHOMA, TENNESSEE, AND EIGHTEEN AND THREE-FOURTHS ONE-HUNDREDTHS TO THOMAS TAYLOR, OF NASHVILLE, TENNESSEE.

STEAM-BOILER.

1,152,421.

Specification of Letters Patent.

Patented Sept. 7, 1915.

Application filed July 21, 1913. Serial No. 780,306.

To all whom it may concern:

Be it known that I, THOMAS A. KILLMAN, citizen of the United States, residing at Nashville, in the county of Davidson and State of Tennessee, have invented certain new and useful Improvements in Steam-Boilers, of which the following is a specification.

My invention relates to steam boilers and the primary object of my invention is to provide means whereby the otherwise waste products of combustion from the boiler furnace may be utilized to preheat the feed water of the boiler.

15 A further object of the invention is the provision of a boiler and preheater so constructed that all the heat from the ordinary waste products of combustion will be absorbed in the preheater so that the products of combustion will pass off in a cool condition and thus the usual waste of heat units nearly eliminated.

20 A further object of the invention is the provision of a boiler and preheater so constructed that a comparatively small amount of water is passing through the boiler proper at any one time, the preheater, however, having a larger cubical content so that the comparatively large amount of water in the preheater shall be submitted to the action of the waste products of combustion.

25 A further object of the invention is to provide means whereby the products of combustion coming from the boiler furnace may be positively directed through the tubes of the preheater and from this carried off through a flue.

30 A further object of the invention is to provide means whereby the products of combustion from the boiler furnace may be directed either to and through the preheater and pass off through the flue, or may be diverted directly to the flue.

35 A further object of the invention is the provision of means whereby exhaust steam may be used to cause a forced draft of the products of combustion through the preheater.

40 A further object of the invention is to so construct the preheater and arrange it in relation to the boiler that the temperature

of the water as it rises through the preheater will be gradually raised and the water in the upper portion of the tubes of the preheater be heated before passing to the boiler proper. 55

Further objects will appear in the course of the following description.

My invention is illustrated in the accompanying drawings, wherein:

Figure 1 is a longitudinal vertical section 60 through my improved flue on the line 1—1 of Fig. 2. Fig. 2 is a top plan view of the boiler, the stack or flue 13 being in section. Fig. 3 is a section on the line 3—3 of Fig. 1.

Referring to these drawings 2 designates 65 a boiler casing of any suitable construction but illustrated as a vertically disposed cylindrical shell. The lower portion of this casing 2 forms an ash pit designated 3 into which a door 4 opens, and above the ash pit 70 is disposed the grate 5 upon which the fire is supported, a door 6 opening into the fire box so formed. Immediately above the fire box is the boiler proper, consisting of a circumferential casing wall 7 and upper and lower 75 flue sheets, and a plurality of vertical flues or tubes 8 extend through the boiler space and open through the upper and lower sheets. The heated products of combustion 80 pass from the fire box through these tubes and are discharged into the chamber 9 which forms the upper end of the shell 2.

Disposed adjacent to the shell 2 is the preheater or absorber. This comprises a shell 10 illustrated as cylindrical and vertically disposed, this shell at its upper end being generally conical in form as at 11 and from the upper end of this conical head 11 extends a duct 12 which opens into the chamber 9. The lower end of the shell 10 85 which forms the absorber or preheater is connected to a flue or chimney 13 of any suitable character.

Disposed within the shell 10 is a casing 14 having a circumferential wall and upper and lower walls. Extending between these upper and lower walls and opening upon the outer face thereof are the tubes or flues 15 arranged like tubes in a water tube boiler. The space within the casing 14 is to be filled 100 with water designed to be preheated while the heated products of combustion passing

through the duct 12 pass down through the head 11, through the tubes 15 and into the lower portion of the shell 10 below the casing 14 and from this pass out through the flue 13. A water supply pipe 16 enters the shell 10 and casing 14 at the lower end of the latter and a pipe 17 or other form of duct extends between the upper portion of the casing 14 and the bottom 7 of the boiler proper. Thus the water contained within the absorber or preheater passes out through the pipe or duct 17 into the lower portion of the boiler and is there submitted to the direct action of the fire in the fire box and the action of the heated products of combustion passing through the tubes 8.

The flue or duct 12 is also connected directly to the flue 13 by means of a transversely extending flue or pipe 18 as illustrated in Fig. 2 and disposed within this flue or bypass is a valve 19 illustrated as a butterfly valve, this valve being provided with a stem which is provided with a handle 20 exteriorly of the flue whereby it may be manipulated.

For the purpose of causing a forced draft in the duct or flue 12, thereby causing the positive carriage of the heated products of combustion from the chamber 9 into the head 11 and so downward through the tubes of the preheater or absorber, I provide an exhaust steam pipe 21, which extends to the engine and which is adapted to carry the exhaust from the engine into the flue 12. It will be seen that the exhaust steam discharged through the pipe 21 into the flue 12 will create a suction in this flue 12 which will cause the heated gases in the chamber 9 to be positively drawn along the flue 12 and discharged in the head 11. In other words, this exhaust pipe will cause a circulation of these heated gases.

A steam pipe 22 extends from the upper portion of the boiler casing to the engine.

It is to be particularly noted that the boiler proper is a comparatively small upright tubular boiler and that the absorber or preheater 10 is located so that its upper end is about on a level with the lower end 50 of the boiler proper. Cold water is pumped into the water supply pipe 16 until the absorber or preheater is entirely filled. Then the water passes by way of pipe 17 into the boiler and is maintained at the proper level. Now as the heated gases from the flue 12 pass down through the small tubes in the absorber or preheater the heat contained in these tubes will be absorbed by the water and the gases will eventually pass out 60 through the tubes practically cool. Since the heated gases come in contact with the upper end of the absorber 10 first and since the heat of these gases is gradually absorbed as they pass down through the tubes, 65 the water in the upper part of the preheater

or absorber will always be hotter than in the lower portion and since heated water tends to rise owing to expansion and also specific gravity and owing to the fact that water is a very bad conductor of heat, this condition 70 of graduated temperature from the top to the bottom of the absorber or preheater will always be maintained. In other words, water can be at boiling point in the top of the absorber while the water is practically 75 cold in the bottom of the absorber. Only the hottest water in the absorber will be supplied to the boiler and as the hot water is fed from the top of the absorber or preheater the colder water below rises to take 80 its place and is in turn heated by the descending heated gases.

It is to be particularly noticed that the boiler is smaller than the absorber or preheater. The reason for this is that it is a 85 waste of fuel to maintain a large flow of water at the steaming point or boiling point, when there is only a comparatively small amount of this water to be converted into steam and used at any one time. It is better to maintain a comparatively small amount of water at the intensely heated steaming point by having the heat applied directly to it and then have a supply of 90 slightly cooler water but still very hot, from 95 which the boiler may be fed as required. As with my invention this extra supply of hot water is furnished by the otherwise wasted hot gases, a great saving of fuel is effected and a much better and more even supply of 100 steam is secured as there is never any cold water pumped into the boiler. The water entering the boiler is always nearly as hot as the water then contained in the boiler. It will be noted, of course, that the exhaust 10 steam also acts to heat the water in the absorber or preheater and that this exhaust steam is caused to do work, thus eliminating another source of waste.

The lower portion 23 of the shell 10 below 11 the lower wall of the casing 14 forms a chamber for catching the water of condensation. Water of condensation will gather in this chamber 23 to a predetermined level and it will be noted that the tubes 15 of the preheater and absorber project down below the lower wall of the casing 14 so that the lower ends of the tubes are immersed to a slight degree in this water of condensation. A drain pipe 24 is provided whereby the 12 height of this water may be regulated and the shell 10 is provided with a hand-hole 25 whereby access may be had to the interior of the chamber 23 so as to clean it out. The object of providing this water seal in the 13 chamber 23 is as follows: The highly heated vapor passing over from the boiler furnace and down through the shell 10 and tubes 15 will be condensed and this condensation will 14 be caught in the chamber 23. I have found 15

by experience that this water of condensation will hold suspended in it almost all of the particles of carbon which may have passed over from the furnace and that whatever waste products pass up through the stack or chimney 13 will be almost entirely clear of carbon particles. Thus this particular form of boiler furnace will eliminate the objectionable smoke nuisance. This elimination of carbon particles from the cooled products of combustion which pass up through the chimney 13, will be further effected by reason of the tubes 15 projecting down a slight distance into the water of condensation. This causes the products of combustion to be forced to a slight extent through the water which will catch and hold any carbon particles which may not have been in suspension in the water of condensation passing downward through the lower portions of the tubes 15. The exhaust steam will also be condensed on its passage through the tubes 15 and the water of condensation will be caught in the chamber 23. I have found in actual practice that the gases and products of combustion will be entirely cooled by the passage through the tubes 15, thus showing that all of the heat contained in these gases has been absorbed by the water in the preheater or absorber. Thus all of the heat units contained in these otherwise waste gases will be caused to do work. It may be pointed out that it is absolutely necessary that the heated products of combustion shall be forced down through the preheater instead of up therethrough in order to secure the function of my apparatus. In other words, the products of combustion at their greatest heat act upon the highest portion of the water first and gradually pass downward through cooler areas until they issue into the chamber 23. If the products of combustion were taken into the lower ends of the tubes 15 and passed upward a uniform temperature would be secured throughout the entire mass of water whereas with my construction a graduated temperature is secured. I have found in practice with my invention that absolutely cold water may be present in the lower portions of the tubes 15 while the water in the upper portions of the tubes is nearly at the steaming point.

There is another point which is of vital importance to this invention. It is a well known fact that it is impossible to pump water at or near the steaming point into a boiler, the reason being that when the piston of the pump moves back the reduction in pressure within the pump chamber will cause the water to be converted into steam. By my construction cold water may be pumped into the lower portion of the absorber or preheater and this water at or near the steaming point will readily pass into the

lower portion of the boiler by means of the duct 17. No cold water, therefore, is pumped into the boiler proper except when the boiler is first fired.

While I have illustrated what I believe to be the best form of my invention, I do not wish to be limited thereto as it is obvious that it may be changed in many ways without departing from the spirit of the invention. Nor do I wish to be limited to the use of my heat absorber with a steam boiler as it is obvious that it may be used wherever it is desirable to utilize hitherto wasted products of combustion passing from a furnace.

Having described my invention, what I claim is:

1. The combination with a boiler furnace and boiler having a relatively small water heating cubical content, of a preheater having a relatively large water heating cubical content including a casing adapted to contain feed water and connected at its upper end directly to the lower end of the boiler, fire tubes passing down through the casing, means for passing products of combustion from the furnace into direct contact with the boiler and then downward through the fire tubes of the preheater, and means for admitting feed water into the lower end of the preheater.

2. The combination with a boiler and furnace, of a preheater including an outer casing, the upper end of the preheater being approximately on a level with the lower end of the boiler, a water container disposed within the casing, fire tubes passing through the water container and opening into the upper and lower portions of the casing, an inlet pipe entering the water container at its lower end, an outlet pipe extending directly from the upper end of the water container to the lower end of the boiler, a flue extending from the boiler and furnace to the upper end of the said casing, and a discharge flue extending from the lower end of the casing of the preheater, said preheater having a much greater cubical content than the boiler.

3. In a boiler, an outer shell, a boiler proper supported above the fire box in said shell, fire tubes passing through the boiler and opening at their lower ends into the fire box and at their upper ends into the space above the boiler, a preheater comprising an outer shell, a casing supported within the preheater, the upper end of said casing being approximately on a level with the lower end of the boiler, fire tubes passing through the casing and opening at their upper ends into the space above the casing and having their lower ends open and extended into the space below the casing, the cubical content of the boiler being smaller than the cubical content of the preheater,

a flue connecting the space above the boiler to the space above the casing in the pre-heater, and a discharge flue extending from the lower portion of the preheater casing, 5 the upper portion of the preheater casing being connected by a horizontal duct with the lower portion of the boiler.

4. In an apparatus of the character described, a vertical shell, a fire box therein, 10 a boiler disposed in said shell above the fire box and comprising upper and lower sheets and vertical fire tubes, the fire tubes opening at their lower ends into the fire box and at their upper ends discharging into the 15 upper portion of the shell, a feed water heater comprising a shell, a water container disposed in the said shell and having vertical fire tubes extending therethrough opening at their lower ends into the lower portion 20 of the shell and at their upper ends into the upper portion thereof, the upper end of the water container being disposed approximately on a level with the lower end 25 of the boiler, the content of the feed water heater being considerably larger than the content of the boiler, a duct connecting the upper portion of the water container with the lower portion of the boiler, an inlet pipe leading into the lower portion of said water 30 container, a flue connecting the upper portion of the furnace shell with the upper portion of the preheater shell, a discharge flue leading from the lower portion of the preheater shell, a by-pass flue connecting the 35 first named flue with said discharge flue, and a valve in said by-pass flue.

5. The combination of a boiler and furnace, of a heat absorbing preheater having a greater cubical content than the boiler and 40 including an outer casing, a water container

disposed within the casing, fire tubes passing through the water container and opening into the upper and lower portions of the casing, the lower portion of the casing constituting a water collecting chamber and the 45 lower ends of said tubes extending a distance into said chamber, an inlet pipe entering the water container at its lower end, an outlet pipe extending transversely from the upper end of the water container directly 50 to the lower end of the boiler, a flue extending from the boiler and furnace to the upper end of the casing, a discharge flue extending from the lower end of the casing of the preheater, and means for maintaining 55 a water seal in the lower end of said container.

6. The combination of a fire box, a boiler disposed immediately over the fire box, fire tubes extending vertically through the boiler 60 from the fire box to a space above the boiler, a preheater water container having its upper end substantially level with the lower end of the boiler, a single straight tube connecting the upper end of said water container with the lower end of the boiler, a conical head over the upper end of said container, a smoke flue leading from the space above the boiler into said head, a smoke flue leading from the space below said container, an ejector in the first-mentioned smoke flue, and a water supply pipe entering the lower end of the water container. 70

In testimony whereof I affix my signature in presence of two witnesses.
